INVENTOR:

Christian Latschar,

BY Drake Co. ATTY'S.

UNITED STATES PATENT OFFICE.

CHRISTIAN LATSCHAR, OF NEW BRUNSWICK, NEW JERSEY, ASSIGNOR OF
ONE-HALF TO JOSEPH HINGHER, OF SAME PLACE.

TOY FOR FORMING SOAP-BUBBLES.

SPECIFICATION forming part of Letters Patent No. 430,999, dated June 24, 1890.

Application filed March 26, 1890. Serial No. 345,356. (No model.)

To all whom it may concern:

Be it known that I, CHRISTIAN LATSCHAR, a citizen of the United States, residing at New Brunswick in the county of Middlesex and State of New Jersey, have invented certain new and useful Improvements in Toys for Forming Soap-Bubbles; and I do hereby declare the following to be a full, clear, and exact description of the invention, such as will enable others skilled in the art to which it appertains to make and use the same, reference being had to the accompanying drawings, and to letters of reference marked thereon, which form part of this specification.

15 The object of this invention is to enable a collection or plurality of soap-bubbles to be formed simultaneously, and which, when blown to a sufficiently large size, will unite and form a connected group of bubbles very pleasing to the eye.

The invention consists in the arrangements and combinations of parts, substantially as will be hereinafter set forth, and finally embodied in the clauses of the claim.

25 Referring to the accompanying drawings, in which like letters indicate corresponding parts in each of the several figures, Figures 1 and 2 are elevations taken from different points of view. Fig. 3 is a bottom plan of the same. Figs. 4 and 5 are detail views of a wind-wheel which may be employed in connection with the bubble-forming parts of the device, and Fig. 6. is a section taken on line *x*.

35 In said drawings, *a* indicates a small hollow body, preferably of tubular section, to one side or end of which the ends of small branching pipes or tubes *b b b* are secured. The flaring ends, or the ends which lie opposite the said body *a*, are provided with bowls *c c*, adapted to be dipped into the soapy water or suds from which the bubbles are formed, and form a film which being enlarged by blowing through the branching tubes produces the desired bubble. The said bowls lie in or approximate a given plane in position, so that they may be dipped into the water

simultaneously. The hollow body *a* also receives a tubular mouth-piece *d*, by which the breath of the person using the device is conveyed to the body *a*, and from thence to the branching tubes. Said body may also be provided with a handle *h* for holding the device in position, and a plug or stopper *g* for closing an opening to the chamber in the hollow body, by means of which said opening the interior of said body may be cleansed from time to time. The said plug *g* may provide bearings for a wind-wheel *f*, and the tubular mouth-piece may be provided with a branch tube *e*, adapted to direct the breath onto the wings of said wheel, and thus cause the latter to revolve. Thus the player may by a single puff of the breath form a plurality of bubbles and revolve the wind-wheel, as will be apparent.

The handle *h* and the wind-wheel *f* and tube *e* may be dispensed with.

What I claim as new is—

1. The bubble-forming toy herein described, combining a mouth-tube and a group or plurality of tubes *b* connected therewith, substantially as and for the purposes set forth.
2. The bubble-forming toy herein described, combining with a tubular mouth-piece branch tubes *b b*, each having a bowl at the end thereof, substantially as set forth.
3. The bubble-forming toy herein described, combining with the hollow body *a* a mouth-piece *d* and flaring branch tubes *b b*, each having a bowl *c*, substantially as and for the purposes set forth.

4. In combination with the hollow body *a*, the branches *b b*, provided with bowls, a mouth-tube, and a plug *g*, substantially as set forth.

In testimony that I claim the foregoing, I have hereunto set my hand this 22d day of March, 1890.

CHRISTIAN LATSCHAR.
